Atty.*

UNITED STATES PATENT OFFICE.

FRANK L. ORDWAY, OF SALEM, MASSACHUSETTS, ASSIGNOR TO PARKER BROS., OF SALEM, MASSACHUSETTS, A CORPORATION OF MAINE.

GAME.

Application filed April 8, 1922. Serial No. 550,647.

To all whom it may concern:

Be it known that I, FRANK L. ORDWAY, a citizen of the United States, and a resident of Salem, in the county of Essex and 5 State of Massachusetts, have invented an Improvement in Games, of which the following description, in connection with the accompanying drawings, is a specification, like characters on the drawings representing 10 like parts.

This invention relates to a move indicating or counting device for games.

In order that the principle of the invention may be readily understood, I have dis- 15 closed a single embodiment thereof in the accompanying drawing, wherein—

Fig. 1 is a plan view of one form of device embodying my invention;

Fig. 2 is a similar view, but with the top 20 removed, so that the interior construction may be seen; and

Fig. 3 is a vertical section upon the line 3—3 of Fig. 1.

The device of my invention is capable of 25 use in many relations which it is unnecessary to enumerate. As instancing two uses only for the device, it is pointed out that it may be employed to indicate the number of spaces that pieces are to be moved in a board 30 game, such, for example, as parchesi, and it may be employed in much the same way as a die box is used.

Referring more particularly to the drawing, a closed receptacle is indicated at 1. 35 It is of any desired shape, but is herein represented as triangular, since this form best adapts itself to the purpose of the device. The receptacle may be of any desired material, such, for example, as wood or paste- 40 board or metal. The said receptacle has desirably two compartments, namely, a wholly closed compartment 2 and a much smaller compartment 3, the latter having an observation element 4, such as glass, celluloid, or 45 the like. Said two compartments 2, 3 are in communication by means of a passage 5 which permits the entrance of a single body only of the series of balls or other movable bodies 6. Preferably the bodies 6 are 50

55 spherical, but they may be of any suitable shape, provided they can be readily moved and desirably rolled from the larger into the smaller compartment. The bodies 6 contrast with each other in any desired manner, such, for example, as by differently col-

oring them, thereby giving them different values. Thus, for example, if six balls be employed, they may be respectively colored red, orange, yellow, green, blue and violet. The compartment 2 is provided with a top 60 7 of opaque material, preferably forming a permanent or fixed part of the receptacle. The transparent cover 4 for the smaller opening is also desirably a fixed part of the receptacle. 65

Preferably the base 8 of the receptacle is inclined as indicated at 9 from the rear wall 10 toward the passage 5, so that when the device is placed flatwise upon the table, the balls tend to roll toward the passage 5, 70 the diameter of the latter being such that only one of the balls can enter the smaller compartment and there be observed through the transparent cover 4.

In using the device, it is turned into up- 75 right position, that is, at a position at right angles to that indicated in the drawings and is given a shake in the same manner that a dice box is shaken. This causes the balls 6 to move about in the larger compartment 2, 80 which is of sufficient size in all dimensions to permit this. The device is then turned into horizontal position, and preferably is laid flatwise upon the table where the game 85 is being played. One of the balls 6 is thus caused to roll through the opening 5 into the smaller compartment 3 where it is observed through the transparent cover 4. The value of the ball which has rolled into the compartment 3 is noted by reason of its 90 color or other distinguishing characteristic, and the proper move is accordingly made in the game, or such ball is otherwise availed of.

Desirably at each side of the passage 5 95 there are inclined guides 11, 12, within the larger compartment 2, so as to direct the balls 6 toward the opening 5 and so as to prevent jamming or wedging of the balls at the opening. 100

Having thus described one illustrative embodiment of my invention, I desire it to be understood that although specific terms are employed, they are used in a generic and descriptive sense and not for purposes 105 of limitation, the scope of the invention being set forth in the following claims.

Claims:

1. A move indicating or counting device for games comprising in combination, a 110

- closed receptacle having a wall adapted to form a base, said receptacle containing a series of small movable pieces having different values, said receptacle having a portion 5 within the confines of said base restricted to the reception of a single movable piece, said portion provided with an observation opening into position beneath which the pieces may be moved singly by chance. 50
- 10 2. A move indicating or counting device for games comprising in combination, a receptacle one wall of which is adapted to form a base, said receptacle having a larger compartment closed from observation and a 55 smaller compartment communicating therewith and provided with an observation opening, a series of small movable bodies within said device and adapted after agitation of the device to move toward the smaller compartment into which only one can enter at a time and be observed through the said observation opening. 60
- 15 3. A move indicating or counting device for games comprising in combination, a receptacle including a base adapted to rest flatwise upon a support, a large and a small closed compartment upon and together defined by said base, a series of small movable objects within said receptacle and all of 65 30 which are adapted to be received at one time in the larger compartment but only one at a time in the smaller compartment, and restricting means providing a passage for a single object from the larger to the smaller 70 compartment the latter having a window for the observation of the single object passing by chance into the smaller compartment. 75
- 35 4. A move indicating or counting device for games comprising in combination, a receptacle having a wall adapted to act as a base, a relatively large closed compartment

2 and a smaller compartment 8 in juxtaposition thereto upon said base, said compartment 3 having an observation cover 4 of transparent material, a passage 5 between said compartments and a series of balls 6 of contrasting values, said smaller compartment being adapted to receive one ball only of said series at a time for the purpose set forth. 50

5. A move indicating or counting device for games comprising in combination, a flat-based box triangular in horizontal section and having opaque walls, said box including a larger compartment 2 defined by the base and the greater portion of the sides of the triangular box, and a smaller compartment 3 at the apex of the triangle and within the confines of said base and communicating with said larger compartment through a restricted opening 5, said smaller compartment having an observation cover 4, and a series of contrastingly colored balls 6 in said box, one only of which at a time can enter the compartment 3 for observation. 65

6. A move indicating or counting device for games comprising in combination, a box having a closed compartment 2 and a smaller compartment 3 in communication therewith through a restricted opening, a smaller compartment having a transparent cover, the bottom of the larger compartment being inclined toward the compartment 3, and a series of small movable objects of contrasting values adapted to be agitated within the compartment 2 and to roll toward the compartment 3 when the device is placed flatwise upon a support. 75

In testimony whereof, I have signed my name to this specification.

FRANK L. ORDWAY.
